UNITED STATES PATENT OFFICE.

JOHN P. McMAHON, OF BUFFALO, NEW YORK, ASSIGNOR TO THE McMAHON THERMOGRAPH COMPANY, OF JERSEY CITY, NEW JERSEY.

THERMOSTAT.

SPECIFICATION forming part of Letters Patent No. 426,304, dated April 22, 1890.

Application filed October 7, 1889. Serial No. 326,181. (No model.)

To all whom it may concern:

Be it known that I, JOHN P. McMAHON, a citizen of the United States, residing in Buffalo, in the county of Erie and State of New York, have invented certain new and useful Improvements in Thermostats, of which the following description, in connection with the accompanying drawings, is a specification.

My invention relates to thermostats employed for automatically breaking the connections of a normally-closed electric circuit and completing the connections of a normally-open electric circuit when the temperature at the place where the instrument is placed has risen to a predetermined degree.

The object of the invention is to provide an instrument that will respond uniformly when subjected to a given amount of heat, will be free from liability to derangement by dust or by shocks, will be reliable under all circumstances, and will be easily repaired.

The invention consists in the construction and arrangement of parts as hereinafter described and claimed.

In the accompanying drawings, wherein like letters and numerals of reference indicate like parts in the several figures, Figure 1 is a plan view of my improved thermostat. Fig. 2 is a similar view of the same with a portion of the casing removed. Fig. 3 is a partly-sectional view of the same, and Fig. 4 is a sectional view on a plane at right angles to the plane of Fig. 3.

Upon a suitable insulated base A four spring metal strips or contact-pieces are secured. Strips 1 and 2 are connected to binding-posts B' and B², to which are attached the terminals of the normally-closed circuit. These strips are in electrical contact when the instrument is in its normal condition—that is, when closed ready to send a fire-alarm. They complete the circuit from post B' to post B², and are held in contact with each other by the insulated post P. The strips 3 and 4 are connected to binding-posts B³ and B⁴, to which are attached the terminals of wires forming part of the normally-open circuit. These strips are separated when the thermostat is closed, but complete the normally-open circuit when the thermostat is operated by heat. The strips are inclosed in a stout metal case O, which

has a screw-threaded aperture, into which a threaded tube T is screwed. The exposed end of the tube is sealed by a thin disk, preferably of brass, which is soldered to the body of the tube with solder, which fuses at a degree 55 of temperature previously determined. The outer end of post P rests against this disk and its inner end rests against the spring contact-piece 2. The post is reduced in diameter near its inner end, forming a shoulder p. The reduced portion is passed through a hole p' in the piece 4, in order that the lower end of the post may rest against the piece 2, which underlies the piece 4. The shoulder p rests against the piece 4. 60

When the tube T is screwed into the case O, the insulated rod P forces strips 1 and 2 into contact and separates strips 3 and 4, holding them apart, thus completing the normally-closed circuit and breaking the normally-open 70 circuit. When the temperature rises beyond the degree at which the solder fuses, the disk D is freed from tube T, post P is released, strips 1 and 2 separate, thus breaking the normally-closed circuit, and strips 3 and 4 75 contact, thus closing the normally-open circuit. In this manner two distinct signals are transmitted upon the two circuits in case of fire, and the transmission of false alarms, caused by derangement of either circuit, is 80 prevented.

It will be seen that the strips are held positively in their normal position and cannot be caused to make or break contact by shocks or vibration of the wall or ceiling to which 85 the thermostat is secured. As the electrical contacts are inclosed in a stout and tight case, they are protected from injury by violence and from derangement by dust. If the thermostat has been used, all that is necessary is 90 to unscrew the tube and replace it with another.

I claim—

1. The combination of a case, a tube formed with threads to engage said case and to be held against movement, a disk secured to the tube with fusible solder, fixed contact-points and two independent spring contact-points forming the terminals of two different electrical circuits, and an insulated post adapted to rest against said disk and to engage both of said 95 100

spring-contacts and hold them against the spring-pressure, as and for the purpose described.

2. The combination of a case having an aperture, a tube engaging said case, a disk secured to the tube with fusible solder, an insulated post formed with a shoulder, spring contact-pieces 1 and 2, held in contact by the lower end of said post, and spring contact-pieces 3 and 4, held out of contact by the shoulder of said post, as and for the purpose described.

3. The combination of a case having a screw-threaded aperture, a threaded tube engaging said aperture, a disk secured to the tube with fusible solder, an insulated post formed with a reduced lower end and a shoulder, spring contact-pieces 1 and 2, held in contact by the lower end of said post, and spring contact-pieces 3 and 4 overlying said first-

named contact-pieces and held out of contact by engagement with the shoulder of said post, as and for the purpose described.

4. The combination of the insulated base A, the case O, having a screw-threaded aperture, the threaded tube T, engaging said aperture, the disk D, secured to the tube with fusible solder, the insulated post P, formed with a shoulder, spring contact-pieces 1 and 2, held in contact by the lower end of said post, and spring contact-pieces 3 and 4, held out of contact by the shoulder on said post, as and for the purpose described.

In witness whereof I affix my signature in presence of two witnesses.

JOHN P. McMAHON.
